(57) **CLAIM**

The ornamental design for an enema bottle with perforated shrink-wrapped tamper seal, as shown and described.

DESCRIPTION

FIG. 1 is a front perspective view of an enema bottle with perforated shrink-wrapped tamper seal showing our new design;

FIG. 2 is a front elevation view thereof;

FIG. 3 is a rear elevation view thereof;

FIG. 4 is a left-side elevation view thereof;

FIG. 5 is a right-side elevation view thereof; and,

FIG. 6 is a top plan view thereof.

The stippling is meant to represent the appearance of a shrink-wrapped portion. The parallel dotted lines on the shrink-wrapped portion represent perforations and form part of the claimed design.
